UNITED STATES PATENT OFFICE.

WILLIAM SUSTINS, OF WAUPACA, WISCONSIN.

IMPROVEMENT IN WEATHER-STRIPS.

Specification forming part of Letters Patent No. **170,029**, dated November 16, 1875; application filed October 21, 1875.

To all whom it may concern:

Be it known that I, WILLIAM SUSTINS, of Waupaca, in the county of Waupaca and State of Wisconsin, have invented certain new and useful Improvements in Weather-Strips; and I do hereby declare that the following is a full, clear, and exact description thereof, which will enable others skilled in the art to which it appertains to make and use the same, reference being had to the accompanying drawings, and to the letters of reference marked thereon, which form a part of this specification.

The nature of my invention consists in the construction and arrangement of a weather-strip, as will be hereinafter more fully set forth.

In the annexed drawing, Figure 1 is a front view of a door embodying my invention, with the bottom end of the door in vertical section. Fig. 2 is a cross-section through the line *xx*, Fig. 1. Fig. 3 is a section through the line *yy*, Fig. 1.

A represents an ordinary door hung in the door-frame *B*. In the bottom edge of the door is made a longitudinal groove, extending the entire length of the door. In this groove is placed a strip of wood, *C*, to the bottom edge of which is fastened a rubber tube, *D*, and the strip is held in the groove by means of two spiral springs, *a a*. In the hanging post of the frame *B* is fastened a small stub, *E*, having a rounded end, as shown. In closing the door the end of the strip *C* passes under the rounded part of the stub *E*, which presses it down onto the sill of the frame. On the shutting-post of the frame is a wheel, *G*, under which the other end of the strip *C* passes to press the rubber tube down on the sill, thereby making a close joint the entire length of the sill, which will keep out all wind, rain, snow, dust, &c. Through the center of the strip *C* is a pin, *b*, of wood, work-

ing in a slot, *e*, in each side of the groove. This pin prevents the weather-strip from pushing endwise while passing under the stub *E*. The weather-strip thus constructed is entirely hid within the door, and the rubber does not drag on the sill, for as soon as the ends of the strip clear the stub and wheel the springs *a* draw the weather-strip upward again. In the ends of the strip *C*, at the points where the stub *E* and wheel *G* touch the same, are inserted screws, for the purpose of regulating the weather-strip, so that in case of the sill wearing away after a time a slight turn of these screws to raise them will press the weather-strip down that much more, making the rubber fit the step or sill as close as at first.

The weather-strip can at any time, when desired—for instance, in the summer time—be thrown out of use to give ventilation by simply removing the stub *E* and wheel *G*, when the strip will remain drawn up in the groove.

Having thus fully described my invention, what I claim as new, and desire to secure by Letters Patent, is—

1. The combination, with a door, *A*, having a groove in its lower end, of the wood strip *C*; rubber tube *D*, springs *a a*, and guide-pin *b*, working in the slots *e*, substantially as and for the purposes herein set forth.

2. The stub *E* and revolving wheel *G*, in combination with the weather-strip *C D*, substantially as and for the purposes herein set forth.

In testimony that I claim the foregoing as my own I affix my signature in presence of two witnesses.

WILLIAM SUSTINS.
